UNITED STATES PATENT OFFICE.

GEORGE M. GRAHAM, OF CHICAGO, ILLINOIS, ASSIGNOR TO G. A. EDWARD KOHLER, OF CHICAGO, ILLINOIS.

REINFORCING-FRAME FOR CONCRETE STRUCTURES.

No. 910,470.

Specification of Letters Patent.

Patented Jan. 19, 1909.

Original application filed December 10, 1907, Serial No. 405,888. Divided and this application filed May 6, 1908.
Serial No. 431,085.

To all whom it may concern:

Be it known that I, GEORGE M. GRAHAM, a citizen of the United States of America, and a resident of Chicago, in the county of Cook and State of Illinois, have invented certain new and useful Improvements in Reinforcing-Frames for Concrete Structures, of which the following is a specification.

This invention relates to skeleton reinforcing frames for concrete structures in which the skeleton centers of the frame are formed of series of links of the hoop type arranged in separated relation upon marginal supporting frames. And the present improvement has for its object to provide a simple and convenient arrangement of said series of links, adapted to aid in the easy and economical erection of the skeleton reinforcing frame, all as will hereinafter more fully appear.

20 In the accompanying drawings:—Figure 1, is a side elevation a bundle of links of the hoop type. Fig. 2, is a top view of the same. Fig. 3, is an enlarged fragmentary top view of the same. Fig. 4, is a plan view illustrating the method of erecting the skeleton reinforcing frame.

Similar numerals of reference indicate like parts in the several views.

The present subject matter is a division of 30 the invention originally set forth in my prior application for patent for reinforcing frames for concrete structures Serial Number 405,888, filed December 10, 1907, and comprises in part the same construction and arrangement 35 of parts described in such prior application, as follows:

1 represents a series of vertical posts or columns to which a series of horizontal girders 3 are secured in right angle relation by 40 suitable corner fittings 2, preferably of the type shown in my Patent No. 865,489, of September 10, 1907. Four of such girders connected as described constitute the border frame or a single unit of the reinforcing frame 45 for a concrete structure, and additional units will utilize in their formation, a girder of the next adjacent unit or units.

4 is the skeleton web or center for each unit aforesaid, and which consists of a multiplicity of independent wire links, of the hoop type, which encircle the cylindrical border members of a unit in spaced relation and in crossed directions, to provide an open web like centering for the unit, to which the con-

crete mass forming the main portion of the 55 floor or other portion of the structure is attached, as usual.

The feature of novelty in the present improvement consists in forming the aforesaid links of a uniform and counterpart size and 60 form, and securing the same together side by side into a compact bundle by means of twisted tie wires 5 near the respective ends of the bundle, and with the individual links of the bundle in spaced relation to permit of 65 an interleaving of the adjacent ends of two of the bundles together in the erection of the reinforcing structure in manner set forth in detail in my aforesaid application for Letters Patent Serial No. 405,888. 70

Arranged in the manner above described, the bundle of links constitute a very compact article which can be shipped from the place of manufacture to the place of erection and there applied to the cylindrical frame members in a ready, rapid and economical manner. In the manufacture of said links an electric weld 6 is preferred for imparting the required endless nature to said links during the process of making the same, other usual 80 and suitable fastening means may however be employed without departing from the scope of the present invention. 75

The following are the series of steps or operations mooted in the method of erection 85 above referred to: The series of vertical posts 1 are erected, after which the initial bundle 4' of links is slipped upon the initial girder 3' after which said girder is raised and coupled to its supporting posts. The 90 second bundle 4'' of links is then slipped inside or over the initial bundle 4' of links, as found most convenient, and in right-angle relation, after which the second girder 3'' is passed through one end of the bundle 95 4'' of links and then coupled in place on and to its supporting posts. At this stage in the erection of a reinforcing structure having two or more units in adjacent relation, the bundle 4''' of links of the next adjacent 100 unit will be interleaved with the wire links of the bundle 4' previous to the next operation, to-wit: The third girder 3''' is then slipped into the bundle 4'' of links, and the fourth girder 3'''' through the interleaved 105 links of the bundles 4' and 4'' after which such girders 3''' and 3'''' are moved to place and coupled to their supporting posts to com-

plete the preliminary erection of the first unit. The succeeding units are erected by a repetition of the steps above set forth. With the completion of the preliminary erection of 5 one or more units, the links comprising the center thereof are spread apart into the required spaced relation and the required or predetermined tensioning of the same is effected by imparting in a manual and individual manner, more or less obliqueness to 10 the links in relation to the marginal frame.

Having thus fully described my said invention what I claim as new and desire to secure by Letters Patent, is:—

15 1. As an element in reinforcing frames for concrete structures, a bundle of links of the elongated hoop type and of uniform and standard size secured together side by side

in spaced relation to permit of an interleaving of the adjacent ends of two bundles of 20 links together.

2. As an element in reinforcing frames for concrete structures, a bundle of links of the elongated hoop type and of uniform and standard size, and twisted tie wires arranged 25 near the respective ends of the bundle and securing the links together side by side in spaced relation to permit of an interleaving of the adjacent ends of two bundles of links together.

Signed at Chicago, Illinois, this 2nd day of May 1908.

GEORGE M. GRAHAM.
